UNITED STATES PATENT OFFICE.

WILLIAM C. CODDINGTON, OF BALTIMORE, MARYLAND, ASSIGNOR OF TWO-
THIRDS OF HIS RIGHT TO CALVIN S. SHRIVER AND HENRY D. SHRIVER,
OF SAME PLACE.

WRENCH.

SPECIFICATION forming part of Letters Patent No. 231,763, dated August 31, 1880.

Application filed June 7, 1880. (No model.)

To all whom it may concern:

Be it known that I, WILLIAM C. CODDINGTON, of Baltimore, Maryland, have invented a new and useful Improvement in Wrenches; 5 and I hereby declare the following to be a full, clear, and exact description of the same.

My invention is an improvement upon wrenches of the class in which the movable jaw is made to slide upon the shank, and is held 10 upon said shank at any required point by means of a plate, serrated or smooth, pressed upon the said shank by means of a cam pivoted in the jaw itself.

In implements of this class the details are 11 of importance, since they relate to the easy and unobstructed movement of the movable jaw and to its firm hold upon the shank. Both of these requirements are essential to the practical operation of such implements.

20 My invention consists in the combination of a serrated holding-plate (whether used with or without compensating plates) with a peculiar form of recess or chamber in the movable jaw of the wrench and in hereinafter-described 25 relation to the cam which presses said jaw upon the serrated edge of the shank.

In the drawings hereunto attached, and forming part of this specification, Figure 1 is a side elevation of the wrench, with movable jaw in 30 section. Figs. 2 and 3 represent details hereinafter explained. Fig. 4 is a section of the jaw separate from the wrench, and Fig. 5 is a central transverse section of the same. Fig. 6 shows a modification in which a thumb-screw 35 is substituted for a cam.

In these drawings, A represents the movable jaw. It is considerably elongated, and is provided with two straps, *a a*, which surround the shank of the wrench. Opposite the interior surfaces of these two straps are corresponding abutments, which form the opposite side of the opening through which the shank slides. Between these two abutments is a recess, *b*, fitted to receive a block, *c*, the face of which is serrated to fit at any point the serrated edge 45 of the shank.

In a slot, *g*, formed in the lower side of the movable jaw, is pivoted the cam-shaped end of a handle, *e*, the cam of said handle being adapted

to bear against the lower side of the block *c* 50 and to press it against the serrated edge of the shank, so as to hold the jaw securely at any required point.

What has been described above in these more general terms has been shown partly in 55 the patent of McManus, No. 14,571, of April 1, 1856, and partly in the patent of Knisely, No. 109,913, of December 6, 1870; but my invention more particularly relates to the form of the recess which contains the block and to the 60 block itself. This recess is shown more particularly in Fig. 5. It is formed with four sides and with a bottom, *b'*, upon which the block may rest without coming in contact, necessarily, with the cam. The block *c* is fitted securely but loosely in this recess, so that it may 65 freely rise and fall therein.

The cam-shaped lever *e* works in a slot narrower than the bottom of the recess into which it opens, and the cam is so formed that when the 70 lever is pressed into a position approximately parallel with the shank it holds the block firmly against the serrated edge of the shank; but when the lever *e* is turned into the position shown in Fig. 4 it permits the block to drop to 75 the bottom of the recess, and consequently to ride freely over the serration of the shank.

As the rectangular block fits within the recess of corresponding shape, when it is free from the cam, it is guided accurately by the 80 sides and moves freely without any liability to bind, and the movable jaw may be slipped back and forth without danger of sticking upon the way.

The cam should be so shaped that when it 85 is brought to bear upon the block its projecting edge will wedge against such block and hold the handle stationary until forcibly moved.

In event of wear upon the block *c* the compensating plate or plates *f*, Fig. 3, may be 90 placed in the bottom of the recess underneath the block, where they will be held accurately by said bottom parallel with the block and the face of the shank.

I have thus endeavored to overcome, on the 95 one hand, the difficulties sought to be avoided in the patent of McManus by attaching the block to a spring, and, on the other, the diffi-

culty likely to arise from binding and the im-
possibility of using compensating plates where
the block rests against the edge of the cam by
which it is pressed down.

5 It will be understood that when the handle
is turned as in Fig. 4, the cam face drops below
the bottom of the recess.

Having thus described my invention, what I
claim is—

10 In combination with the serrated shank of
a wrench, a movable jaw provided with a re-

cess, *b*, a cam-lever, *e*, and a block, *c*, having
a serrated side and adapted to move freely in
the recess and to rest upon the bottom thereof,
substantially as described.

15 In testimony whereof I have signed my name
to this specification in the presence of two sub-
scribing witnesses.

WILLIAM C. CODDINGTON.
